UNITED STATES PATENT OFFICE.

CHARLES G. BRIGHT, OF NEENAH, WISCONSIN, ASSIGNOR TO PAPER PATENTS COMPANY, OF NEENAH, WISCONSIN, A CORPORATION OF WISCONSIN.

COLOR-DEPOSITING APPARATUS FOR PAPER-MAKING MACHINES.

Application filed October 7, 1926. Serial No. 139,972.

This invention relates to the art of wall paper manufacture, having reference more particularly to a type of wall paper generally known as tiffany paper, wherein the color effects are incorporated in the paper during the process of manufacture of the latter, as distinguished from subsequent printing, by means of a liquid color, or a number of different liquid colors, sprayed onto the surface 10 of the web during the travel of the latter on the wire screen in machines of the Fourdrinier type.

The color spraying apparatus of the present invention is designed to produce a paper having a variegated or mottled appearance wherein the different colors run into and are blended with each other on the surface, thus creating in the latter regions of different colors which, however, are not sharply defined 20 but, as stated, overlap and blend or shade into each other, creating a variegated cloud effect.

Among the objects of the present invention are to provide an improved and simplified 25 chrome blast apparatus adapted to spray the liquid color vertically onto the surface of the web, to provide such an apparatus wherein the width of the spray striking the web may be varied through vertical adjustment of the 30 downwardly directed spraying nozzles or guns relatively to the surface of the web, to provide such an apparatus wherein the spray may be delivered intermittently, rather than continuously, and during its delivery may 35 have a reciprocating movement relatively to the web and crosswise of the latter, to provide an improved automatic valve-actuating mechanism for the spray guns, and to provide an apparatus that may be adjusted to 40 change the color scheme by affording different relatively timed movements of the valve-actuating and controlling devices of different sprayers or groups of sprayers.

Still other objects and attendant 45 advantages of the invention will be apparent to persons familiar with the art as the same becomes better understood by reference to the following detailed description, taken in connection with the accompanying drawings, 50 wherein I have illustrated one practical embodiment of the principle of the invention, and in which:

Fig. 1 is a side elevation of the color de-

positing apparatus and its driving mechanism, showing the wire screen and paper web 55 carried thereon in cross-section;

Fig. 2 is a top plan view of the sprayers and their actuating devices;

Fig. 3 is a vertical transverse section taken on the line 3—3 of Fig. 1;

Fig. 4 is a detail side elevation of one of the spraying guns and its actuating mechanism; and

Fig. 5 is a diagram, illustrating the general order or arrangement of depositing the several colors on the web, and the relation of the actuating cams of the sprayer guns thereto, but without showing the overlapping and blending of marginal regions of the variously colored spots.

Referring to the drawings, 10 designates the usual wire screen web conveyor of a Fourdrinier machine, and 11 designates the end roll of the machine over which the wire screen passes and by which it is driven. 12 75 designates the paper web which is delivered through the usual flow box to the screen, spread thereon by the usual slices, and drained by the usual suction boxes. These parts of the paper machine are not illustrated 80 as they form no part of the present invention.

On opposite sides of the screen 10 are erected on suitable foundations 13 four rectangularly disposed columns 14, two on each side; and between the columns of each pair 85 is a bracket 15 formed at its ends with sleeves 16 slidably mounted on the columns 14 and secured in adjusted position by set screws 17. On each of the brackets 15 are mounted a pair of pedestals 18 (Fig. 3) formed on their 90 adjacent sides with bearing bosses 19 (Fig. 1) in which are slidably mounted a pair of parallel rods 20. The columns 14 above the rods 20 are rigidly connected and braced by longitudinal angle bars 21 and transverse 95 angle bars 22.

Mounted on each of the rods 20 are spaced clamp collars 23 (Fig. 3), and in lateral bosses 24 on the outer sides of said collars are mounted a series of sprayers or guns designated as an entirety by 25, each terminating at its lower end in a spray nozzle 26. Supported on cross-bars 27 resting on the horizontal limbs of the angle bars 22 are a series, herein shown as four, of color manifolds 28, each equipped with an overlying

return flow manifold 29. Tapped into the lower sides of the manifolds 28 are faucets 30 each equipped with a valve 31, and depending from said faucets are hose 32 leading downwardly into the sprayers 25. In the arrangement shown, the hose 32 from a pair of color manifolds on one side lead into alternate sprayers in one row, and the hose 32 from the two color manifolds on the other side lead into alternate sprayers of the other row, so that the sprayers of one row deliver two colors in alternating arrangement and the sprayers of the other row also deliver two colors in alternating arrangement. Suspended from the rods 20 as by loop hangers 33 (Fig. 1), or otherwise suitably supported, are a pair of compressed air manifolds 34, from which hose 35 also lead into the several sprayers. Where the compressed air manifolds are suspended from the reciprocating rods 20, the open ends of the air manifolds 34 are connected to a compressed air supply pipe 36 by flexible hose 37 of sufficient length to accommodate the reciprocating movements of the compressed air manifolds.

Rigidly mounted in seats in the upper ends of the pedestals 18 are a pair of bars 38 each formed on its upper edge with a group of uniformly spaced peak cams 39; the cams of one bar being preferably offset substantially midway of the peaks of the other bar. On each of the collars 23 is an upwardly extending arm 40 terminating in a laterally offset vertical fork 41 that straddles and extends slightly above the cam peaks 39 of the bars 38. The limbs of each fork 41 are themselves vertically slotted to receive a shaft 42 on which is journaled a roller 43 riding on the upper edge of the cam bar 38. The ends of the shaft 42 overhang the limbs of the fork, and from their overhanging ends is suspended a U-shaped link 44 carrying on its lower end a hook 45 that is engaged with a clevis 46 that, in turn, embraces the trigger 47 of the sprayer gun, the raising of the trigger opening a valve in the gun which permits the sudden discharge of the liquid color under the air blast furnished from the compressed air manifolds 34. As the sprayer gun herein shown is old and well known and no novelty is claimed therefor, the structural details thereof are not herein shown. It may be noted, however, that the volume of the blast may be adjusted by turning an adjusting valve 48 normally locked in set position by one or more nuts 49. From the foregoing it will be seen that as the rollers 43 ride over the cams 39, the triggers of the guns will be suddenly raised, permitting a charge of coloring liquid to be sprayed directly downwardly onto the underlying web of paper.

The rods 20 may be reciprocated in suitably timed relation to the travel of the paper web by mechanism such as that illustrated in Figs. 1 and 2, as follows: 50 designates a

main drive shaft carrying at one end a spur gear 51 meshing with and driving a spur gear 52 on the shaft of the end roll 11. Keyed to the shaft 50 is a sprocket wheel 53 which, through a sprocket chain 54, drives 70 a sprocket wheel 55 fast on a countershaft 56. This latter, through bevel gears 57 and 58 drives a shaft 59 journaled in bearings 60 on a base plate 61 supported on a pier 62. On shaft 59 are sprocket wheels 63 which, 75 through sprocket chains 64, drive sprocket wheels 65 fast on a pair of endwise aligned shafts 66 journaled in bearings 67 on standards 68 on the base plate 61. On the inner opposed ends of shafts 66 are crank discs 69 80 carrying wrist pins 70 herein shown as set 180° apart and having equal throws. Pitmen 71 connect the wrist pins 70 with the ends of the rods 20. With this arrangement, the rods 20 are simultaneously reciprocated 85 to equal extents in opposite directions.

Fig. 5 illustrates diagrammatically the manner in which the various colors are sprayed on the surface of the paper web. Assuming that the latter is traveling in the direction indicated by the arrow, at a point in the travel of one of the rods 20 (herein indicated as at the end of its travel) the cams operating the guns carried by said rod serve to discharge the latter, depositing on the paper web the first, third and fifth rows of color spots, the spots in each row presenting alternately the two colors discharged by alternate sprayers. Simultaneously the spots indicated by the second, fourth and sixth rows 100 are deposited by the sprayer guns mounted on the other rod 20, the spots in said rows also alternating between the two colors discharged by said second row of sprayer guns. At the top of Fig. 5 are shown the relative positions 105 of the two cam bars, when the colors are deposited in the manner above described. In this diagram the color spots are shown as sharply defined in order to illustrate the principle of operation; but it is to be understood that in actual practice the marginal portions of the spots overlap and blend to a greater or less extent depending upon the vertical adjustment of the sprayer guns above the surface of the web. Manifestly, the higher the guns are set, the greater will be the diameters of the spots, and the greater will be the extent to which they will overlap and blend into each other.

The relative positions of the spots, and the 110 ultimate coloring effect or color scheme can be widely varied by either changing the relative positions of the actuating cams or by varying the reciprocating relation of the rods 20, or both; for instance, the wrist pins 70 115 on the crank disc 69, instead of being set one hundred and eighty degrees apart so as to effect simultaneous travels of the two rows of sprayers in opposite directions, may be set ninety degrees apart so as to effect a syn- 120

chronous reciprocation of the rods. Also, the speed of operation of the sprayer guns relatively to the speed of travel of the paper web may be varied as, for instance, by providing 5 on the hub of the cam drive sprocket 55 a sprocket of a different diameter, such as the smaller sprocket shown at 55', the driving sprocket 53 being shiftable along the drive shaft 50 to register with either of the 10 sprockets 55 and 55'. These adjustments, together with the vertical adjustability of the sprayer guns, render the apparatus very flexible, and make possible the production thereby of widely varying color effects when using 15 a single assortment of colors.

I have herein illustrated and described one simple and practical embodiment of the principle of the invention which, in practice, has been found to satisfactorily effectuate its 20 stated purposes and objects; but manifestly the details of structure and arrangement may be considerably varied from those shown without changing the principle or sacrificing any of the advantages of the invention, and 25 hence I do not limit the latter to the particular apparatus herein presented except to the extent clearly indicated in specific claims.

I claim:

1. In an apparatus of the character described, the combination of a traveling web carrier, a group of color-spraying guns mounted above said carrier, and means synchronized with the carrier for operating said guns intermittently.

2. In an apparatus of the character described, the combination of a traveling web carrier, a group of color-spraying guns mounted above said carrier, means for effecting relative reciprocating movement of said guns and carrier, and means for effecting substantially vertical discharges from said guns onto the web at a predetermined point in each to and fro movement.

3. In an apparatus of the character described, the combination of a traveling web carrier, a horizontal row of color-spraying guns mounted above and crosswise of said carrier, means for effecting endwise reciprocation of said row of guns, and means for effecting substantially vertical discharges from said guns onto the web at a predetermined point in each to and fro movement.

4. In an apparatus of the character described, the combination of a web carrier, columns opposite the sides of said carrier, vertically adjustable supporting members on said columns, a gun support slidably mounted on said supporting members, color-spraying guns mounted on said gun support, and means for reciprocating said gun support.

5. In a color blast machine, the combination with a traveling web carrier, of spraying guns mounted above said carrier and equipped with discharge-controlling trig-

gers, means for reciprocating said guns crosswise of said carrier, and means for pulling said triggers during each to and fro movement of said guns.

6. In a color blast machine, the combination with a traveling web carrier, of a row of spraying guns mounted above and crosswise of said carrier and equipped with discharge-controlling triggers, means for reciprocating said row of guns endwise, and cam actuated means for pulling said triggers during each to and fro movement of said guns.

7. In a color blast machine, the combination of a traveling web carrier, spraying guns mounted above said carrier and equipped with discharge-controlling triggers, means for reciprocating said guns sidewise, fixed cams, and trigger-pulling mechanisms actuated by said cams during each to and fro movement of said guns.

8. In a color blast machine, the combination of a traveling web carrier, a row of spraying guns mounted above and crosswise of said carrier and equipped with discharge-controlling triggers, means for effecting endwise reciprocation of said row of guns, a fixed bar parallel with said row, cams on said bar, and trigger-pulling mechanisms actuated by said cams during each to and fro movement of said row of guns.

9. In an apparatus for making tiffany paper, the combination of a traveling web carrier, a plurality of groups of spraying guns mounted above said carrier, means for supplying different colors to the guns of the respective groups, and means for effecting simultaneous movements of said groups in opposite directions relatively to and crosswise of said carrier.

10. In an apparatus for making tiffany paper, the combination of a traveling web carrier, parallel rows of spraying guns mounted above said carrier, means for supplying different colors to the guns of the respective rows, and means for effecting simultaneous endwise reciprocating movements of said rows in opposite directions crosswise of said carrier.

11. In an apparatus for making tiffany paper, the combination of a traveling web carrier, parallel rows of spraying guns mounted above said carrier, means for supplying different colors to the guns of the respective rows, means for effecting simultaneous endwise reciprocating movements of said rows in opposite directions crosswise of said carrier, and means for discharging the guns of the respective rows at corresponding points in the travel of the latter.

12. In a color blast machine, the combination of a web carrier, a row of color-spraying guns mounted above said carrier, and synchronized means for effecting endwise

travel of said web carrier and reciprocating travel of said rows crosswise of said web carrier; said means including means for changing the speed ratio between said web carrier and said rows of guns.

13. In a color blast machine, the combination of a web carrier, a supporting and driving roll on which said carrier is mounted, a gun carrier reciprocably mounted above and crosswise of said web carrier, downwardly discharging spraying guns mounted on said gun carrier, a drive shaft, driving connections from said drive shaft to said roll, and driv-

ing connections from said drive shaft to said gun carrier.

15

14. In an apparatus of the character described, the combination of a traveling web carrier, a plurality of groups of color nozzles mounted above said carrier and adapted to deposit liquid of different colors upon the web beneath and means synchronized with the carrier for intermittently operating said nozzles according to a predetermined plan, so as to stagger the deposits of like color along said web.

CHAS. G. BRIGHT.
